UNITED STATES PATENT OFFICE.

WILLIAM JACOBS OSTERMAN, OF RICHMOND, VIRGINIA.

DESIGN FOR A FORK-SCRAPER.

SPECIFICATION forming part of Design No. 23,173, dated April 10, 1894.

Application filed February 6, 1894. Serial No. 499,302. Term of patent 3½ years.

To all whom it may concern:

Be it known that I, WILLIAM JACOBS OSTERMAN, a citizen of the United States, residing at Richmond, in the county of Henrico and State of Virginia, have invented and produced a new and original Design for Fork-Scrapers, of which the following is a specification, reference being had to the accompanying drawing, wherein the figure is a perspective view showing my design.

The leading feature of my design consists in a scraper blade having a notched or serrated formation produced at its lower edge.

The blade A is at one end of the shank rod

B and is set at an obtuse angle to said rod with the notched or serrated formation a at its free edge or edge opposite its juncture with the handle B. The handle B is straight throughout its length except the upwardly deflected formation C as clearly shown in the drawing.

What I claim is—

The design for a fork scraper herein shown and described.

WILLIAM JACOBS OSTERMAN.
